UNITED STATES PATENT OFFICE.

TERRENCE L. CRAWFORD, OF GRAFTON, WEST VIRGINIA, ASSIGNOR OF ONE-HALF TO
WILLIAM T. CRAWFORD, OF PENSACOLA, FLORIDA.

CAR-COUPING.

1,207,871.

Specification of Letters Patent. Patented Dec. 12, 1916.

Application filed February 14, 1916. Serial No. 78,216.

To all whom it may concern:

Be it known that I, TERRENCE L. CRAWFORD, a citizen of the United States, residing at Grafton, in the county of Taylor and State of West Virginia, have invented certain new and useful Improvements in Car-Couplings, of which the following is a specification, reference being had to the accompanying drawings.

This invention relates to certain improvements in car couplings and it is an object of the invention to provide a coupling of this general character wherein the knuckle is pivotally mounted in applied position without the necessity of a knuckle pin, whereby a coupler is produced possessing a maximum of strength and whereby the parting of trains is prevented which has often occurred when couplings are employed using knuckle pins.

It is also an object of my invention to provide a novel and improved car coupler whereby the knuckle may be readily and conveniently applied in operative position.

The invention consists in the details of construction and in the combination and arrangement of the several parts of my improved car coupling whereby certain important advantages are attained and the device is rendered simpler, less expensive and otherwise more convenient and advantageous for use, all as will be hereinafter more fully set forth.

The novel features of the invention will hereinafter be definitely claimed.

In order that my invention may be the better understood, I will now proceed to describe the same with reference to the accompanying drawings, wherein—

Figure 1 is a view in elevation illustrating a coupler constructed in accordance with an embodiment of my invention; Fig. 2 is a view partly in top plan and partly in section of my coupler as herein embodied; Fig. 3 is an elevational view, detached, of my improved knuckle; and Fig. 4 is a fragmentary view partly in plan and partly in section of a portion of my improved draw head.

As disclosed in the accompanying drawings, 1 denotes a draw head of a conventional type having its outer end provided with the transversely disposed substantially horizontal open slot 2, the opposed walls of which being provided with the vertically

aligned transversely disposed open end recesses 3, the open ends of which being disposed outwardly.

4 denotes a knuckle of predetermined type including the inwardly disposed tail piece 5 and the inner or connected end of the tail piece 5 is provided on opposite faces with the vertically disposed trunnions 6 adapted to be received within the recesses 3, whereby it will be perceived that the knuckle 4 may be readily and conveniently mounted in applied position. The trunnions 6 are of materially large diameter whereby it will be perceived that the possibility of the same being fractured is substantially entirely avoided.

After the knuckle 4 is properly applied to the draw head 1, the pin 7 is applied in operative position, said pin 7 being disposed through the vertically aligned openings 8 produced in the head 1 and intersecting the recesses 3, said openings 8 being so positioned relative to the inner ends of the recesses 3 as to substantially contact with the outer surface of the tail piece 5, whereby it will be perceived that the knuckle 4 is effectively maintained against displacement, although it will be readily appreciated that when it is desired to remove the knuckle 4, it is only necessary to remove the pin 7. Attention is also directed to the fact that the outer edge of the tail piece 5 immediately adjacent the knuckle 4 proper, is curved on a radius concentric to the axes of the trunnions 6, whereby the knuckle 4 and tail piece 5 will be capable of pivotal movement about the trunnions 6 without the pin 7 offering any obstruction thereto.

In order to positively hold the pin 7 against accidental displacement, I find it of advantage to dispose therethrough a cotter pin 9 or the like which is preferably positioned within the uppermost recess 3, whereby it will be perceived that the pin 7 is held against such upward movement as would unseat the same from within the openings 8. It is also to be observed that the opening 8 in the lower wall of the slot 2 does not extend entirely through the adjacent portion of the head 1. I also wish to particularly note that the upper and lower faces of the head 1 are convexed in order that the head may be materially strengthened.

From the foregoing description, it is thought to be obvious that a car coupling

constructed in accordance with my invention
is of an extremely simple and comparatively
inexpensive nature and is particularly well
adapted for use by reason of the conven-
5 ience and facility with which it may be as-
sembled, and it will also be obvious that my
invention is susceptible of some change and
modification without material departure
from the principles and spirit thereof and
10 for this reason I do not wish to be under-
stood as limiting myself to the precise ar-
rangement and formation of the several
parts herein shown in carrying out my in-
vention in practice.

15 I claim:

A car coupling comprising a draw head
provided with a transverse slot, the opposed
walls of the slot being provided with trans-

versely directed open recesses, a knuckle
having trunnions extending from opposite
faces thereof, said trunnions being insert-
ible within the recesses in the opposed walls
of the slot of the head, and a pin removably
20 inserted through the head and intersecting
the recesses, said pin being engageable with
the adjacent edge of the knuckle when in
applied position, the adjacent edge of the
knuckle being arranged on a curve concen-
25 tric to the axes of the trunnions of the
knuckle.

30 In testimony whereof I hereunto affix my
signature in the presence of two witnesses.

TERRENCE L. CRAWFORD.

Witnesses:

W. E. LAWSON,
C. M. FORREST.
